US0D1057596S

(12) **United States Design Patent** (10) Patent No.: **US D1,057,596 S**
(45) Date of Patent: ** Jan. 14, 2025

(54) **ARTICLE OF JEWELRY**

(71) Applicant: **LOUIS VUITTON MALLETIER**,
Paris (FR)

(72) Inventors: **Francesca Amfitheatrof**, Paris (FR);
Paul Harrison, Paris (FR); **Naomi Brown**, Paris (FR)

(73) Assignee: **Louis Vuitton Malletier**, Paris (FR)

(**) Term: **15 Years**

(21) Appl. No.: **29/859,279**

(22) Filed: **Nov. 9, 2022**

(30) **Foreign Application Priority Data**

May 12, 2022 (FR) 20222134

(51) **LOC (15) Cl.** **11-01**

(52) **U.S. Cl.** **D11/92**
USPC **D11/92**
